N-(ALKYLHALOPHENYL) DERIVATIVES OF LEUCAURAMINE

Clyde S. Adams, Yellow Springs, and Marjorie J. Cormack, Dayton, Ohio, assignors to The National Cash Register Company, Dayton, Ohio, a corporation of Maryland

No Drawing. Application January 10, 1956
Serial No. 558,194

4 Claims. (Cl. 260—570)

This invention relates to the N-(alkylhalophenyl) derivatives of leucauramine, having the general structure

where R is taken from the group consisting of 2-chloro, 3-methyl; 2-bromo,3-methyl; 2-methyl,3-chloro; 2-methyl,3-bromo; 2-chloro,4-methyl; 2-bromo,4-methyl; 2-methyl,4-chloro; 2-methyl,4-bromo; 2-chloro,5-methyl; 2-bromo,5-methyl; 2-methyl,5-chloro; 2-methyl,5-bromo; 3-chloro,4-methyl; 3-bromo,4-methyl; 3-methyl,4-chloro; 3-methyl,4-bromo; 3-methyl,5-chloro; and 3-chloro,5-methyl.

These are solid crystalline materials, relatively colorless, which may be used as color-reactants because they turn to a dark blue or blue-green color on coming into adsorption contact with acidic types of inorganic compounds such as attapulgite, halloysite, kaolin, bentonite, aluminum sulfate, zeolite material, silica gels, magnesium trisilicate, and zinc sulphide, among others, and are useful in solution for printing in color on paper coated or filled with such adsorbents. Otherwise, they are very light-stable and atmospherically-stable both in their leucouramine forms and in their colored states.

The great utility of these compounds, as at present known, is their use in transfer coatings in manifold record systems wherein the rear surface of an overlying sheet of record material is coated with a composition containing one or more of the novel leucauramine derivatives and the underlying sheet containing particles of the acidic reactant. In such manifold systems the leucauramine derivatives or mixtures of them, are usually dissolved in a suitable solvent and carried as droplets in a hydrophilic colloid film coating on the rear of the overlying sheet. When the two sheets are in contact and a printed or written impression is made on the top surface of the overlying sheet, rupturing the film at the points of pressure, the liquid solution is released locally so it may be adsorbed by the acidic particles in or on the under sheet. Such contact will make blue or blue-green marks on the top surface of the under sheet at the points of pressure. Such a manifold system is disclosed in United States Patent 2,712,507 which issued July 5, 1955, on the application of Barrett K. Green.

These alkylhalo derivatives of N-phenyl leucauramine are much more suitable for the manifold systems mentioned than the unsubstituted known N-phenyl leucauramine, because they are less volatile, they have increased solubility in oil, and they are much more stable com-

2

pounds in the leuco form when subjected to the atmosphere and light.

The leucauramine derivatives also are useful in solid powdered form as one of two solid powdered materials placed by an alkylhalo substituted phenyl group.

placed by an anionic substituted phenyl group. The sheet, the second material being one of the acidic inorganic materials which cause a blue or blue-green color to appear when marked with a stylus. Such a record sheet is disclosed in United States Patent 2,505,470 which issued, on the application of Barrett K. Green, on April 25, 1950.

One process of making the novel compounds consists of the steps of condensing molar equivalents of Michler's hydrol and a selected alkylhalo derivative of aniline in hot ethyl alcohol; concentrating the reaction mixture as far as necessary to cause precipitation on cooling; filtering; purifying the crude material by heating a benzene solution of it with fuller's earth and activated charcoal; and then precipitating out the reaction product by the addition of petroleum ether. The general equation for this reaction is as follows:

N-alkylhalo substituted phenyl leucauramine where X is a alkylhalo substituted phenyl nucleus.

Leucauramine itself has the structure

50 The novel derivatives of this invention may be considered as derivatives of leucauramine in that one of the hydrogen atoms attached to the (1) N has been replaced by an alkylhalo substituted phenyl group.

As a first specific example of the process, consider the making of N-(2-methyl,5-chlorophenyl)leucauramine;

55 70.8 grams (0.5 mole) of 2-methyl,5-chloroaniline, and 135.0 grams (0.5 mole) of Michler's hydrol are dissolved in 500.0 grams of ethyl alcohol

60 in a round-bottomed flask fitted with a water-cooled reflux condenser. The solution is refluxed for four hours on a steam bath after which the solution is allowed to cool to room temperature. The crystals which have separated out are filtered off by suction and washed with small amounts of cold ethyl alcohol. The filtrate may be concentrated for additional crops of crystals. The resultant crude product is dissolved in 1½ liters of hot benzene, treated with activated charcoal, and fuller's earth, and filtered. The filtrate is evaporated to approximately 200 milliliters, cooled, and the reaction product precipitated out with petroleum ether. The resulting pure material is

a white crystalline substance. Following is a representation of the reaction:

The other methylchloro and methylbromo derivatives mentioned in the first paragraph of the specification may be made by using a methylchloro or methylbromo aniline with the methyl and chloro or bromo substituents in the desired positions, in the same procedure just outlined with respect to the preparation of N-(2-methyl,5-chlorophenyl) leucauramine, the molecular proportions being the same.

A typical N-(methylbromophenyl)leucauramine is prepared as follows:

93 grams (0.5 mole) of aniline with the bromo and methyl substituents in the desired positions as selected from those set forth in the first paragraph of the specification.

135 grams (0.5 mole) and of Michler's hydrol are dissolved in

200 grams of ethyl alcohol

and the before-mentioned procedure outlined for the preparation of the methylbromo derivatives is followed. The reaction is represented as follows:

It will be obvious to those skilled in the art that the ethylhalo or higher alkylhalo homologs of N-(alkylhalo-phenyl) derivatives of leucauramine may be made in the same manner by use of the selected substituted aniline in the same molecular amounts.

What is claimed is:

1. The derivative compounds of N-(alkylhalophenyl)-leucauramine, having the general structure

where RX is taken from the group consisting of 2-chloro, 3-methyl; 2-bromo,3-methyl; 2-methyl,3-chloro; 2-methyl, 3-bromo; 2-chloro,4-methyl; 2-bromo,4-methyl; 2-methyl, 4-chloro; 2-methyl,4-bromo; 2-chloro,5-methyl; 2-bromo, 5-methyl; 2-methyl,5-chloro; 2-methyl,5-bromo; 3-chloro, 4-methyl; 3-bromo,4-methyl; 3-methyl,4-chloro; 3-methyl, 4-bromo; 3-methyl,5-chloro; and 3-chloro,5-methyl.

- 20 4-bromo; 3-methyl,5-chloro; and 3-chloro,5-methyl.
 2. The compound N-(2-chloro,5-methylphenyl)leu-cauramine, having the structure

3. The compound N-(2-methyl,5-chlorophenyl)leu-cauramine, having the structure

- 45 4. The compound N-(2-methyl,4-bromophenyl)leu-cauramine, having the structure

UNITED STATES PATENT OFFICE
CERTIFICATE OF CORRECTION

Patent No. 2,828,342

March 25, 1958

Clyde S. Adams et al.

It is hereby certified that error appears in the printed specification of the above numbered patent requiring correction and that the said Letters Patent should read as corrected below.

Column 2, line 5, strike out "placed by an alkylhalo substituted phenyl group." and insert instead -- dispersed in a coating on one side of a record material --; column 4, line 33, for "metyl" read -- methyl --.

Signed and sealed this 27th day of May 1958.

(SEAL)
